UNITED STATES PATENT OFFICE.

CHARLES BOOZ, OF BUFFALO, NEW YORK, ASSIGNOR, BY MESNE ASSIGNMENTS, TO GEORGE K. BIRGE, OF SAME PLACE.

DESIGN FOR WALL-PAPER.

SPECIFICATION forming part of Design No. 24,813, dated October 29, 1895.

Application filed September 27, 1895. Serial No. 563,927. Term of patent 3½ years.

To all whom it may concern:

Be it known that I, CHARLES BOOZ, a citizen of the United States, residing at Buffalo, in the county of Erie and State of New York, 5 have invented and produced a new and original Design for Wall-Paper, of which the following is a specification, reference being had to the accompanying drawing, showing a part thereof.

10 The design consists of a series of connected ornamental scrolls arranged in the form of panels with a large vase-like ornament in the center filled with flowers and leaves and connected at its base with said ornamental scrolls,

15 as represented in the accompanying drawing. The border of the design consists of ornamental scrolls with cornucopia-like ornaments connected with said scrolls and filled with flowers and leaves, as shown in the drawing. 20

What I claim is—

1. The design for wall paper herein shown and described.
2. In the design for wall paper, the border herein shown and described. 25

Witness my hand this 24th day of September, 1895.

CHARLES BOOZ.
